Patented July 12, 1927.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed November 3, 1926. Serial No. 145,963.

This invention relates to car roofs and has for its principal object to provide a simple and efficient roof that will readily adapt itself to the distortions of the car body incident to service conditions. Other objects are cheapness of construction, compactness of design, fewness of parts, and ease of assembly.

The invention consists principally in an eaves clip adapted to hold the sheets down on the car at the eaves, said clips being provided with an abutment surface which limits outward sliding movement of the sheets and is shaped to permit the eaves ends of the sheets to rock thereon. The invention also consists in the construction and arrangement of parts hereinafter described and claimed.

In the accompanying drawings, which form part of this specification and wherein like symbols refer to like parts wherever they occur.

Fig. 1 is a plan view of a portion of a car roof embodying my invention, parts being broken away to more clearly illustrate the invention;

Fig. 2 is a vertical transverse section taken at the ridge on the line 2—2 in Fig. 1;

Fig. 3 is a vertical cross section through one of the side seams on the line 3—3 in Fig. 1;

Fig. 4 is a vertical cross section through the car at the side plate on the line 4—4 in Fig. 1;

Fig. 5 is a vertical section through the side plate, the section being taken through one of the eaves clips on the line 5—5 in Fig. 1; and

Fig. 6 is a perspective view of one of the eaves clips.

Referring to the accompanying drawings, my invention is shown in connection with a common type of roof frame or substructure comprising side plates 7, carlines 8, side sheathing 9 and fascia-boards 10. A ridge pole 11 and purlines 12 rest on and are rigidly secured to the carlines; and a series of spaced parallel wooden battens or mullions 13 extend transversely of the car from eaves 14 to eaves thereof across the tops of the side plates, purlines and ridge pole and are rigidly secured thereto. The upper corner of each side plate 7 is rabbeted or offset to a

lower level than the main surface thereof; and the upper edges of the side sheathing 9 and fascia 10 terminate flush with the surface of said rabbet to form outward extensions thereof. A metal eaves flashing strip 14 has a body portion which rests flatwise in said rabbet and has its inner marginal portion 15 rebent or doubled-back over said body portion but spaced slightly therefrom; and the outer margin of said flashing strip is bent down over the fascia and nailed or otherwise rigidly secured thereto.

Supported on the side plates, ridge pole and purlines between adjacent battens are metal roof sheets 16, which extend from eaves to ridge of the car. Said roof sheets are of less width than the spaces between battens and are spaced apart at their ridge ends. The metal roof sheets have their eaves end portions rebent on the under side, as at 17, to interlock movably with the doubled-over inner marginal flanges 15 of the eaves flashing strips 14. The ridge margins of the sheets are provided with upstanding seam flanges 18; and the side margins of said sheets are flanged upwardly and are thence bent inwardly over the bodies of the sheets to form side seam flanges 19 of substantially inverted L-shaped section. The side seam flanges 19 of the sheets on opposite sides of the battens are loosely connected to each other by inverted channel-shaped transverse seam covers 20 that straddle said flanges and said battens and have outstanding base flanges 21 that rest on the body portions of said sheets. The transverse seam covers have downwardly curved eaves end portions that merge into the plane of the base flanges of said seam covers at the ends thereof where they are rebent on their under sides, as at 22, beneath corner portions of the doubled-under eaves end flanges 17 of the roof sheets.

The spaced ridge ends of the sheets are loosely connected by ridge seam covers 23 of substantially inverted channel-shaped section which straddle the spaced ridge flanges 18 of adjacent sheets and have outstanding base flanges 24 that rest on the body portions thereof. The adjacent ends of the transverse seam covers 20 and the ridge seam covers 23 are secured to the car by the usual four-way corner or center caps 25 which are

provided with downwardly opening cross grooves or channels that straddle said ends of said seam covers. The corner caps 25 are secured to the ridge pole by vertical bolts 26, which also secure the running board saddles 27 in position. Running boards 28 rest on said saddles and are secured thereto in any suitable manner.

Located at the eaves of the car, midway between adjacent roof battens or mullions, are eaves clips 29. Each of said eaves clips comprises a body portion which rests flatwise on the body portion of the eaves flashing strips 14 and a depending outer end portion or flange 30, which overhangs the depending flange of said eaves flashing and is rigidly secured to the car preferably by means of horizontal bolts 31. The body portion of said eaves clip extends inwardly beneath the doubled-under eaves flange 17 of the roof sheet beyond the free edge thereof and has its inner marginal portion rebent or doubled-back to form a flange 32 which extends between said doubled-under flange of said roof sheet and the doubled-back flange 15 of the eaves flashing 14. The doubled-back flange portion 32 of the eaves clip terminates in a depending abutment flange 33 having an outstanding lip 34 at its lower edge. As shown in the drawing, the free marginal portion of the doubled-under eaves flange 17 of each sheet is offset upwardly beneath the doubled-back flange portion 32 of the eaves clip to form an upstanding shoulder 35 adapted to abut against depending abutment flange 33 of said eaves clip and thereby limit the outward sliding movement of the sheet. As shown in the drawing, the depending abutment flange 33 of the clip is bowed or curved from end to end of said flange, the direction of curvature being such that said abutment flange presents a convex surface to the shouldered portion 35 formed by the upwardly offset free marginal portion of the doubled-under eaves flange 17 of the sheet.

By the arrangement described, each roof sheet has pivotal tangential contact midway of its eaves ends with the convex abutment surface of an eaves clip, and is thus adapted to accommodate itself automatically to the distortions of the car frame by a rocking or sluing movement of its eaves end portion on said convex abutment surface. The eaves clips also cooperate with the eaves flashings in holding the sheets down on the car at the eaves; and they also serve to limit sliding or bodily movement crosswise of the car and maintain sufficient clearance or play at the ridge and eaves ends of the sheets to permit the roof sheets to slue on said clips without damage to the sheets, seam covers, or eaves flashings.

The invention is applicable to roofs having various forms of flexible ridge and side

seam constructions and substructures; therefore, I do not wish to be limited to the precise construction shown and described.

What I claim is:

1. A flexible car roof comprising roof sheets whose eaves end portions are rebent, and means cooperating with the rebent eaves end portions of said sheets for securing a sluing movement of said sheets about points located at their eaves ends. 70

2. A flexible car roof comprising roof sheets whose eaves end portions are rebent and formed with shoulders, and a member secured to the car at the eaves and cooperating with the rebent and shouldered eaves end portions of said sheets for holding said sheets down on the car at the eaves and for limiting bodily movement thereof transversely of the car. 80

3. A flexible car roof comprising roof sheets whose eaves end portions are rebent and movably interlocked with rebent flashing strips, and means cooperating with said flashing strips for holding said strips down on the car and with the rebent eaves end portions of said sheets for securing a pivotal movement of said sheets about points located at their eaves ends. 85

4. A flexible car roof comprising roof sheets whose eaves end portions are rebent and movably interlocked with rebent flashing strips, and a member secured to the car adjacent to the eaves ends of each sheet, said member having a portion engaging said flashing strips for holding them down on the car and a portion movably interlocked with the rebent eaves flanges of said sheets and shaped to secure a pivotal movement of said sheet about points located at their eaves ends. 95

5. A flexible car roof comprising roof sheets whose eaves ends are doubled-under, and a clip secured to the car adjacent to the eaves end of each sheet, said clip having a portion cooperating with the doubled-under eaves portion of said sheet, the cooperating portions of said clip and said doubled-under flange being shaped and arranged to hold the sheet down on the car, to limit bodily movement transversely of the car and to secure a pivotal movement of the sheet on said clip. 100

6. A flexible car roof comprising roof sheets having doubled-under eaves flanges that are offset to form shoulders, and a clip secured to the car substantially midway of the eaves end of each sheet and movably interlocked with the doubled-under eaves flange of said sheet, said clip having a convex surface against which the shouldered portions of said eaves flange abuts and on which said shoulder portion is adapted to rock. 115

7. A flexible car roof comprising roof sheets having doubled-under eaves flanges 120

that are offset upwardly beneath said sheets to form shoulders, and a clip secured to the car substantially midway of the eaves end of each sheet and having a doubled-over flange which overhangs the doubled-under eaves flange of said sheet and is provided with a curved portion which cooperates with the shoulder portion of said eaves flange to limit outward sliding movement of said sheet and to secure a rocking movement thereof on said clip.

8. A flexible car roof comprising roof sheets having doubled-under eaves flanges whose free marginal portions are offset upwardly beneath said sheets to provide shoulders, and a clip secured to the car substantially midway of the eaves end of each sheet, said clip having a rebent portion that extends outwardly over the upwardly offset free marginal portion of the doubled-under flange of said sheet and terminates in a depending flange that overhangs the shoulder formed by said offset eaves flange and constitutes an abutment for limiting the outward sliding movement of said sheet.

9. A flexible car roof comprising roof sheets having doubled-under eaves flanges

whose free marginal portions are offset upwardly beneath said sheets to provide shoulders, and a clip secured to the car substantially midway of the eaves end of each sheet, said clip having a rebent portion that extends outwardly over the upwardly offset free marginal portion of the doubled-under flange of said sheet and terminates in a depending flange that overhangs the shoulder formed by said offset eaves flange and constitutes an abutment for limiting the outward sliding movement of said sheet, said flange having a convex surface on which said sheet is adapted to rock.

10. A car roof clip comprising a body portion that is rebent on its upper side, said rebent portion terminating in a depending flange that is bowed from end to end.

11. A car roof clip comprising a strip of metal having a doubled-back end portion spaced from said body portion and terminating in a depending flange that is inwardly bowed from end to end.

Signed at New Kensington, Pa., this 27th day of October, 1926.

CHARLES DAVID BONSALL.
